GRATE BAR FASTENER

Filed May 18, 1931

INVENTOR

Walter H. Clawson
By W. W. Williamson Atty.

UNITED STATES PATENT OFFICE

WALTER H. CLAWSON, OF NORRISTOWN, PENNSYLVANIA

GRATE BAR FASTENER

Application filed May 18, 1931. Serial No. 538,312.

My invention relates to new and useful improvements in a grate bar fastener, and has for one of its objects to provide an exceedingly simple and effective device of this character to temporarily hold or removably secure grate bars against accidental displacement regardless of the general configuration of said bars or the appliance in or on which such bars are assembled.

10 The invention is applicable to stationary or movable grate bars or grate structures or all kinds regardless of the intended use, whether furnaces, boilers, pallets, sintering machines or anything else, but it is particularly valuable for use for holding bars on a supporting frame that has to be tilted or inverted.

Another object of the invention is to rotatably mount a fastening bar or member 20 in a suitable support or supporting frame, which fastening bar is flat or oblong in cross section so as to have short and long diameters and to position said fastening bar for cooperation with a part or parts of a 25 grate bar or bars whereby when the longer diameter of the fastening bar is in a substantially horizontal position, all of the grate bars will be held against accidental displacement or removal but when the fastening bar is turned at right angles any of the grate bars may be removed or replaced.

30 A further object of the invention is to provide for removably mounting the fastening bar and which when in place can be rotated.

A still further object of the invention is to provide a grate fastener including, in combination, any suitable support or supporting frame having an opening through 40 one of the walls of sufficient size to permit the passage of a fastening bar which is rectangular in cross section, the ends of said fastening bar being fashioned to provide trunnions journaled in the walls of the 45 support, the bearing for one of the trunnions preferably being a sleeve fitted into the opening in the support through which the grate bar may pass, said fastening bar cooperating with grate bars provided with 50 transverse circular openings through which

the fastening bar extends and in which said fastening bar is rotatable, said transverse openings having entrance slots leading thereto of a width substantially the same as the shorter diameter or minor dimension 55 of the fastening bar to permit the passage of the grate bar over the fastening bar, but preventing the removal of the grate bar when the fastening bar is turned so that its longer diameter or major dimension lies 60 across the entrance slot.

With these and other ends in view, this invention consists in the details of construction and combination of elements herein-after set forth and then specifically designated by the claim. 65

In order that those skilled in the art to which this invention appertains may understand how to make and use the same, I will describe its construction in detail, referring 70 by numerals to the accompanying drawing forming a part of this application, in which:—

Fig. 1 is a plan view of a conventional grate structure showing a plurality of grate 75 bars mounted upon a support and having interlocking engagement with a fastening bar rotatably mounted in the support as embodied in my invention.

Fig. 2 is a fragmentary sectional view on the line 2—2 of Fig. 1.

Fig. 3 is a fragmentary front elevation of the support and the fastening bar as well as the component parts thereof, but with the grate bars removed. 85

Fig. 4 is a fragmentary sectional view on the line 4—4 of Fig. 3.

Fig. 5 is a slightly enlarged fragmentary sectional view on the line 5—5 of Fig. 4.

In carrying out my invention as herein embodied, 6 represents a suitable support or frame of any desirable size or configuration including end walls 7, so called for convenience of description, on which the ends of grate bars 8, of suitable formation, rest when 90 in operative position. Each grate bar is independent of the others and may be provided with any suitable spacing means 9 located at any suitable place along the bar and of any desirable number. Each grate bar is also 95 100

held against longitudinal movement in any desirable manner, as providing the same with depending lugs 10 which engage the contiguous parts of the frame. Another 5 obvious way to prevent longitudinal movement is to set the ends of the grate bars in a recess or recesses in the end walls 7 of the frame. Of course, the parts are so fitted as to give a certain amount of "play" which 10 will provide for limited longitudinal or transverse movements of the several grate bars.

Each grate bar is provided with a transverse circular opening or hole 11 having an 15 entrance slot 12 leading thereto and I prefer that the hole and the slot be formed in a lobe 13 depending from each grate bar midway the length thereof so that lips 14 are produced for a purpose to be presently 20 described.

The support or frame 6 also includes a rear wall 15 and a front wall 16, the former having a small opening therethrough to provide a bearing for the rear trunnion 17 of 25 the fastening bar 18 while the front wall has an opening 19 therethrough, preferably circular in shape, although other shapes can be utilized, and at least as large as the opening 11 in each grate bar and in said opening 30 19 is removably mounted a sleeve 20 in which a hole 21 is formed to act as a bearing for the forward trunnion 22 of the fastening bar 18. Said bar may be formed with a tool 35 hold 23 for the reception of a suitable tool, handle or crank for readily rotating said fastening bar.

The intermediate part 24 of the fastening bar, or the portion between the trunnions, is 40 of oblong shape in cross section so as to have a long dimension substantially the same as the diameter of the openings 19 and 11 and a shorter dimension substantially equal to that of the width of the slot 12 so that a grate bar may be passed over the flat portion of 45 the fastening bar 24 and the latter then rotated within the opening 11. With the fastening bar in the position shown in Fig. 2, so that its greatest dimension extends cross- 50 wise of the slot 12, said grate bars cannot be displaced because the lips 14 under-lie the flat portion of said fastening bar but when said fastening bar is rotated a quarter turn so that its greatest diameter will be vertical 55 and in alignment with the slots 12 any one or more of the grate bars may be readily lifted and removed from the fastening bar.

The fastening bar is also provided with 60 means to prevent accidental withdrawal thereof or undue longitudinal movement 65 which means may be in the form of pins 25 and 26, said pins being so mounted or constructed as to prevent the same from dropping out when the fastening bar is rotated or when the complete structure is tilted or 70 inverted. One of said pins, as 26, acts as a

holding means or bolt to maintain the fastening bar in a grate bar fastening position or with the greater dimension of the flat intermediate portion in a horizontal position, by engagement with a lug 27 formed on or 70 carried by the front wall 16. This pin can also be utilized to rotate the fastening bar and therefore the tool hold could be eliminated.

When originally assembling all of the 75 grate bars in or on their frame, they can be placed in position and the fastening bar 18 then projected through the opening 19 in the front wall 16 of the frame and through the holes 11 in all of the bars until the rear 80 trunnion 17 is set in its bearing. The sleeve 20 can then be placed upon the forward trunnion 22 and inserted in the opening 19 and finally the pins 25 and 26 inserted, with the pin 26 projecting into or through the lug 27 at which time all of the grate bars will be fastened in position against accidental 85 displacement. By reversing the above actions, all of the grate bars can be removed.

After the entire structure has been 90 assembled and it is desired to remove or replace one or more, but possibly not all, of the grate bars, the pin 26 is withdrawn from the lug 27 and the fastening bar rotated until its longer dimension is vertical or in 95 alignment with the slot 12. This unfastens the grate bars and the one or ones to be removed or replaced can be readily taken off or put back on the fastening bar and when everything is ready, the fastening bar is 100 rotated in the opposite direction until its longer dimension is in a horizontal position crosswise of the slot 12 and so long as the fastening bar is in this position the grate bars cannot be removed.

From the foregoing description, it will be 105 obvious that I have provided an exceedingly simple and effective means for fastening grate bars in position to prevent their accidental displacement as when the frame is tilted to a steep angle or actually inverted.

Of course, I do not wish to be limited to the exact details of construction herein shown and described as these may be varied within the limits of the appended claim 115 without departing from the spirit of my invention.

Having thus fully described my invention, what I claim as new and useful is:—

A grate consisting of a stationary frame 120 having an opening through one of its walls, a sleeve in said opening, a fastening bar having a flat intermediate portion passable through said opening and journaled for rotation in the rear wall of the frame and 125 said sleeve, a plurality of grate bars resting on said frame each having a transverse opening therethrough and a slot leading thereto, said grate bars being individually removable or replaceable when the flat portion of 130

the fastening bar is in alignment with the slots and held against accidental displacement when the flat portion of the fastening bar is crosswise of the slots, a lug on the 5 frame adjacent the position of the fastening bar, and means carried by said fastening bar for engagement with the lug to normally hold the fastening bar against rotation.

In testimony whereof, I have hereunto affixed my signature.

WALTER H. CLAWSON.
